ATTORNEY

UNITED STATES PATENT OFFICE

HAROLD D. STEPHENS, OF ALBANY, NEW YORK

DOORCHECK

Application filed July 11, 1928. Serial No. 291,727.

My invention relates to door checks and disposed aligned extremities, 8, which pass particularly to a device of this character through the openings, 5, in the tongues, 2, adapted to hold a door open. It is particularly adapted for coacting with the outer bumper or buffer which is placed either on the wall or floor behind the door.

The objects of my invention are to provide a device of simple character which may be cheaply constructed, which will comprise a minimum number of elements and which, when the door is closed, will not project an objectionable distance therefrom.

With these objects in view my invention includes the novel elements and the combinations and arrangements thereof described below and illustrated in the accompanying drawings in which—

Fig. 1 is an elevation view of the attaching plate or element before portions thereof are bent outwardly to receive the hook element;

Fig. 2 is a view similar to Fig. 1 showing the hook receiving portions bent outwardly;

Fig. 3 is similar to Figs. 1 and 2 but shows the hook element in position; and

Fig. 4 is a side view of my device including a fragmentary portion of a door and shows how the hook element coacts with the bumper which is attached to the wall behind the door.

Referring to the drawings, 1 indicates a plate element which is used for attaching the device to the door and with which the hook element is hingedly assembled. I have indicated the plate element as elliptical in form but obviously it may be of any shape whatever. Near each extremity of the major axis, are tongues, 2, which are formed by slitting the plate as shown at 3. The sides of these tongues, near the edges, are provided with hemispherical, struck-up portions, 4, and a round hole, 5, which is substantially tangential to the struck-up portions, 4, and is adapted to receive the end, 8, of the hook element. The tongues, 2, are then bent up at right angles to the plate as shown in Figs. 2, 3 and 4.

The hook element, 6, is bent as shown in Figs. 3 and 4 to form a loop adapted to engage the bumper, 7, and having oppositely

It will be obvious that various forms of hooks may be used depending upon the character of the bumper or other object with which it is to coact. Furthermore, it will

be obvious that my check need not necessarily be affixed to the door. It may, if desired, be affixed to the wall and coact with the knob of the door when open.

It is therefore to be understood that the words which I have used are words of

description rather than of limitation and that changes within the purview of the appended

claims may be made without departing from the true scope and spirit of my invention

in its broader aspects.

What I claim is—

1. In a door check, the combination with

a plate adapted for attachment to a door, of

a resilient hook hingedly coacting there-

with; said plate being provided with means

frictionally coacting with the resilient por-

tions of said hook and adapted to resist

movement of said hook to and from its op-

erative position.

2. In a door check, the combination with

a plate provided with a projecting element

having struck-up portions thereon, of a hook

pivoted in said element and frictionally co-

acting with said struck-up portions to main-

tain the hook and plate in fixed relative position.

3. In a door check, the combination with an attaching plate having oppositely disposed portions thereof forming bearings, of a hook element having resilient portions mounted in said bearings, and means coacting with said resilient portions of said hook for retaining it in various positions relative to said plate.

10 4. In a door check of the character described, an attaching plate having spaced tongues provided with openings therein adapted to receive a hook element and means 15 located adjacent to said openings adapted frictionally to resist a turning movement of said hook element therein.

5. In a door check, the combination with a plate adapted for attachment to a door and 20 having supporting means projecting substantially at right angles therefrom, of a resilient hook member pivotally engaged therebetween, and means integral with said supporting means adapted to sustain said 25 hook member in a plurality of desired positions.

6. In a door check, the combination with a plate provided with projecting elements having a hook member pivotally engaged 30 therebetween, of a plurality of inwardly disposed protuberances integral with said projecting elements and adapted to positively maintain said hook member in a plurality of desired positions.

35 7. In a door check, the combination with an attaching plate provided with projecting elements forming bearings, of a hook member having resilient portions freely supported in said bearings, and means coacting with 40 said resilient portions adapted to positively maintain said hook member in a plurality of positions determined by said means.

8. In a door check, the combination with an attaching plate provided with projecting elements having an opening therein adapted 45 to receive a resilient hook element, of a plurality of inwardly disposed protuberances integral with said projecting elements and adjacent the opening therein adapted to 50 coact with said hook member and oppose a substantially small turning force impressed thereupon by external means.

HAROLD D. STEPHENS.
